UNITED STATES PATENT OFFICE.

BRUCE E. SKILES, OF SANTA ANA, CALIFORNIA.

CHOCK FOR AUTOMOBILE WHEELS.

1,407,338.

Specification of Letters Patent. Patented Feb. 21, 1922.

Application filed July 29, 1920. Serial No. 399,946.

To all whom it may concern:

Be it known that I, BRUCE E. SKILES, a citizen of the United States, residing at Santa Ana, in the county of Orange and State of California, have invented new and useful Improvements in Chocks for Automobile Wheels, of which the following is a specification.

This invention relates to chocks for automobile wheels.

It is the object of the invention to provide a chock adapted to be inserted beneath a wheel for preventing movement thereof and in order to steady the wheel. The chock consists of spaced members arranged to be yieldably drawn toward one another so as to engage the wheel at opposite sides of the lowest portion of the periphery thereof. The chock is also provided with means for engaging the wheel so as to withdraw the chock from beneath the same when it is desired to remove the chock.

The invention will be readily understood from the following description of the accompanying drawings, in which—

Figure 1 is a side elevation of the chock showing an automobile wheel positioned upon the same.

Fig. 2 is a top plan view of the chock.

Fig. 3 is a side elevation of the same.

The chock consists of the blocks 1 and 2 which may be formed of wood or any other suitable material. The blocks are adjustably positioned in longitudinal alinement with one another by means of a rod 3 extending along one side of one of the blocks, say the block 1, and slidably received through a sleeve 4 extending along one side of the block 2.

The rod 3 may be connected to block 1 by bolts 5 extending through the rod and the block, and the sleeve 4 may be secured to the block 2 by being received through the eyes of eye bolts 6 extending through the block.

A spring 7 surrounds rod 3 between the blocks 1 and 2, one end of said spring being fixed relative to rod 3 as by having the end 8 of the spring clamped to rod 3 by one of the bolts 5. The opposite end of the spring 50 is secured to the end of sleeve 4. The adjacent ends of blocks 1 and 2 are beveled as shown at 9 and the parts are so arranged that when the blocks are drawn apart

against the tension of spring 7 and the chock then inserted beneath wheel A with the blocks at the opposite sides of the lowermost portion of said wheel, the spring 7 will draw the blocks toward one another so that the wheel will rest against the transverse ridges 10 of the blocks formed at the junction of 60 beveled surfaces 9 with the top surfaces 11 of the blocks. The blocks will thus form a chock for steadyng the wheel and preventing movement thereof.

A handle 12 may be provided at the outer end of block 2 for withdrawing block 2 along rod 3 against the tension of spring 7 when it is desired to remove the chock. A lever 13 is also arranged upon block 12 so as to engage wheel A when it is necessary to exert 70 pressure in order to remove the chock. This lever terminates at its outer free end in a handle 14, and at its inner end is provided with an angularly bent portion 15 having a medially disposed reversely bent portion 16 75 forming a contact arm. The portions 15 of the lever at each side of arm 16 are, preferably, journaled in bearing brackets 17 mounted upon the top of block 2. A clip 18 is, preferably, also mounted upon block 80 2 and is arranged to support lever arm in its operative position.

The arm 16 is angularly disposed relative to lever 13 and is, preferably, provided with an angularly disposed end portion 20. 85 The parts are so arranged that when lever 13 is supported in clip 18, as shown in Fig. 3, the arm 16 will be out of engagement with wheel A, but when lever 13 is swung upon the pivot provided by the portions 15 of said 90 lever the curved arm 16 will be forced against the wheel A, as shown in Fig. 1, for urging block 2 outwardly along rod 3 against the tension of spring 7 and thereby releasing the chock from engagement with the wheel so 95 that the chock may be removed.

Various changes may be made without departing from the spirit of the invention as claimed.

What is claimed is:

1. A chock including spaced blocks, means for yieldably drawing said blocks toward one another, and a lever arranged to force said blocks away from one another.
2. A chock including spaced blocks, means for yieldably drawing said blocks toward

one another to engage a wheel, and a lever other of said blocks received through said pivoted on one of said blocks and having an sleeve, and a spring on said rod secured at arm arranged to engage said wheel when its respective ends to the respective blocks. 10 said lever is actuated for forcing said block In testimony whereof I have signed my 5 away from said wheel and the other block. name to this specification.

3. A chock including spaced blocks, a sleeve on one of said blocks, a rod on the
